(57) **CLAIM**

The ornamental design for a space shuttle lamp, as shown and described.

DESCRIPTION

FIG. 1 is a top, front perspective view of a space shuttle lamp design showing my new design.

FIG. 2 is a front view of a space shuttle lamp.

FIG. 3 is a rear view of a space shuttle lamp.

FIG. 4 is a left side view of a space shuttle lamp.

FIG. 5 is a right side view of a space shuttle lamp.

FIG. 6 is a top view of a space shuttle lamp.

FIG. 7 is a bottom view of a space shuttle lamp; and, FIG. 8 is an enlarged view of a space shuttle lamp taken from the circle part in FIG. 6.

The dash-dash broken line defines the boundary of the enlarged views in FIGS. 6 and 8 and form no part of the claimed design.

The broken lines in the drawings depict portions of the space shuttle lamp that form no part of the claimed design.
